UNITED STATES PATENT OFFICE.

CHRISTIAN JENSEN, OF BATTLE CREEK, IOWA.

HOSE-CLAMP.

1,285,204.

Specification of Letters Patent. Patented Nov. 19, 1918.

Application filed April 1, 1916. Serial No. 88,213.

To all whom it may concern:

Be it known that I, CHRISTIAN JENSEN, a citizen of Denmark, residing at Battle Creek, in the county of Ida and State of Iowa, have invented certain new and useful Improvements in Hose-Clamps, of which the following is a specification.

This invention relates to improvements in hose clamps and its object is to produce a device of this class that is simple and efficient in operation, cheap to manufacture and that is readily moved from operative to inoperative position and vice versa. With the foregoing and other objects in view the invention consists in the combination and arrangement of parts to be herein-after fully described in the following specification, pointed out in the claim and illustrated in the accompanying drawing which forms a part of said specification and in which—

Figure 1 is a front elevation of my improved garment clamp.

Fig. 2 is a side elevation of the same in closed or operative position, the band being eliminated.

Fig. 3 is a view similar to Fig. 2 but with the device open.

Like reference characters indicate corresponding parts throughout the several views.

The reference numeral 1 designates the band which is made of a flexible fabric to encircle the leg of the wearer and is provided with a buckle 2 whereby it may be adjusted to various sizes. To the band a tape or elastic 3 is secured in any suitable manner and the same extends through an elongated metallic loop or band 4 and to 40 and through another elongated metallic loop or band 5 and then back in a plane parallel with itself and terminates in a loop about the first mentioned loop or band 4; the said loop or band 4 is carried at one 45 end of a metal strip 6 and the loop or band 5 at opposite end of the same, said loop or band 5 being provided with a friction roller 7 between which and the said metal strip 6 the upper edge of the hose or other garment to be clamped is drawn. The strip 6, further, is provided with integral parallel ears 8, 8, one edge of each of which is notched

as at 9 and a transverse pin 10 connects the opposite ends of said ears. Upon the said pin 10 the ears 11 of an integral movable 55 jaw 12 are pivotally disposed, said jaw being formed of a single strip of material and having its free end bent inwardly or toward the strip 6 as at 13. Upon the upper side of the jaw 12 an integral sleeve 14 60 is formed through which the longer side 15 of a locking slide extends, the shorter side of said slide being bent back parallel with said longer side and spaced away therefrom and extending outside said sleeve 14 and 65 terminally carrying a pin 16 adapted, when the said slide is in its elevated position shown in full lines in Fig. 2, for locking engagement with the notched portion 9 of the said ears 8. About the said pin 10 the 70 body of a spring 17 is wound, the ends thereof engaging with the metal strip 6 and the jaw 12. When the slide aforesaid is in raised relation the spring will simply put a tension upon the jaw 12 and serve to prevent the accidental displacement of said 75 slide from the notched portion of the ears 8, and in this position the upper edge of the hose or other garment will be retained firmly between said jaw 12 and metallic 80 strip 6; to release the hose the slide 15, 15^a is manually moved toward the free end of the jaw 12 until the pin 16 moves out of engagement with the notched portion of the ears 8 when the spring 17 will force the 85 jaw and connections away from the strip 6 into the position illustrated in Fig. 3 releasing the garment.

What is claimed is:—

In a hose clamp comprising a band provided with an elastic member, a strip provided with terminal loops in engagement with said elastic member, terminally notched ears formed integral with said strip, a pin connecting said notched ears, a swinging 90 jaw pivotally carried by said pin and formed with an inwardly bent termination for engagement with said strip, a spring 95 carried by said pin and having its ends in engagement with the said strip and the said 100 jaw, a sleeve carried by said swinging jaw, a slide arranged upon said jaw and having a long and a short side, the long side of said slide extending through said sleeve, the

short side of said slide being spaced away from said sleeve to form a finger piece, and a pin carried by the looped end of said slide and adapted, in one position of the same, for engagement with the notched ends of said ears to lock said jaw in adjusted relation with said strip.

In testimony that I claim the foregoing

as my own I have hereto affixed my signature in the presence of two subscribing witnesses.

CHRISTIAN JENSEN.
